United States Patent Office.

WILLIAM H. MCPHERSON, OF NASHVILLE, TENNESSEE, ASSIGNOR TO HIMSELF AND WILLIAM N. CARR, SR., OF SAME PLACE.

Design No. 4,708, dated March 14, 1871.

DESIGN FOR FASTENINGS FOR BEDSTEADS.

The Schedule referred to in these Letters Patent and making part of the same.

I, WILLIAM H. MCPHERSON, of Nashville, in the county of Davidson and State of Tennessee, have invented an original Design for a Fastening for Bedsteads, &c., of which the following is a specification.

Nature and Objects of the Invention.

My invention relates to a device primarily intended for connecting the rails and posts of bedsteads, adapted in superior degree to form tight and strong joints, and to dispense with the use of tools and necessity for skilled help in setting up and taking down articles to which it may be applied.

The device consists of a tongue or tenon, applied preferably to the post, a socket therefor, applied preferably to the part, and a locking-wedge, working between shoulders on the respective parts, as herein-after more fully set forth.

My present invention consists in the shape or conformation of the said three several parts.

Description of the Accompanying Drawing.

Figure 1 is a face view of contiguous portions of a bed-post and rail, united by a fastening, illustrating this invention.

Figure 2 is a horizontal section, on the line $z' z'$, fig. 1.

Figure 3 is a perspective of the post part detached.

Figure 4 is a perspective of the rail part.

Figure 5 is a face view of the locking wedge.

Like letters of reference indicate corresponding parts in the several figures.

General Description.

A represents a post, and

B, a rail of a bedstead.

C represents a flat block of metal, to form a tenon, and z a cylindrical stem cast on the same, and provided with a transverse notch, y.

x represents a cavity in the post A, for the reception of the stem z of the tenon C; and

D a pin or screw, passing through the notch y of said stem, to retain the latter.

E represents a metal plate with a facial projection, w, attached to the outer side of the rail B at its end, by screws F, and forming a socket for the tenon C.

v represents a vertical groove in the outer face of the tenon C; and

u, a continuation of the same, cut through the projection w of the socket-plate E.

G represents a wedge, adapted to be driven into the groove v u in the tenon C and socket-plate E, and by acting against the outer shoulders 1 1 of the respective parts of the groove to clamp the said tenon within its socket, and thereby complete the joint.

The parts are released by driving up the said wedge.

The wedge G, and the groove v u for its reception, each have one straight or vertical and one inclined side. The straight side of each is perpendicular; the inclined side perpendicular in the tenon groove v, and dovetailed in the socket groove u. Both sides may be under-cut or dovetailed in the socket groove.

H represents a screw, attaching the wedge G to the socket-plate E; and t a slot in the said wedge, parallel with its straight side, for the reception of said screw.

The parts are adapted to be cast of complete form without the aid of cores.

Claims.

I claim as my invention—

1. The shape or conformation of the tenon C, as shown and described.
2. The shape or conformation of the socket E, as represented and set forth.
3. The shape or conformation of the wedge G, as shown.

WILLIAM H. MCPHERSON.
